UNITED STATES PATENT OFFICE.

CHARLES S. HILL, OF CUMRU, BERKS COUNTY, ASSIGNOR, BY DIRECT AND MESNE ASSIGNMENTS, OF THREE-FOURTHS TO GEORGE L. KNOOPP, JAMES R. MILLER, AND WELLINGTON VAN REED, ALL OF READING, PA.

FRUIT-PICKER.

SPECIFICATION forming part of Letters Patent No. 339,549, dated April 6, 1886.

Application filed September 4, 1885. Serial No. 176,190. (No model.)

To all whom it may concern:

Be it known that I, CHARLES S. HILL, a citizen of the United States, residing in Cumru township, county of Berks, State of Pennsylvania, have invented a new and useful Improvement in Fruit-Pickers, of which the following is a specification.

This invention relates to that class of fruit-pickers which are provided with an elastic tube leading from the picker-jaws to a bag suspended from the shoulders of the operator.

The object of the improvement is to secure an effective picker, easily constructed, readily used, not liable to derangement, and which may be cheaply constructed.

The above objects are attained in the fruit-picker shown in the accompanying drawings, similar letters of reference indicating like parts.

Figure 1 represents in perspective the improved fruit-picker attached to the pole, with the tube leading from the movable jaw to the operator below; Fig. 2, a full front elevation of the same. Fig. 3 represents the jaws or frames divested of their covering, showing the manner in which the wire is wrapped upon the stiffening-bar.

The frames of the picker are usually constructed of spring-wire of about three thirty-seconds of an inch diameter, bent over suitable templets in the form of a wagon-bow. The fixed bow A, which is slightly less in height and width than the movable bow B, has its lower ends, A', left of suitable length to be bent inward toward each other, and these ends are wrapped spirally around a bar, I, in reverse direction relative to each other, with a pitch of about three diameters of the wire, until, meeting at the center of the bar, the extreme ends are left straight and in a vertical position, forming tangs A², for attachment to the pole. The movable bow B is treated in the same manner as to bending to form, and, commencing outside of the fixed bow A upon the bar I, the free ends B' are wrapped spirally between the coils of the ends A' of the fixed bow A until the center of bar I is reached, when the ends are projected forward at right angles with the face of the bows, and at about one inch or more from the bar are recurved to form looped

levers B². An open link, C, connects the looped levers B², and to the same link is attached by an integral eye, D', a spiral re-enforce spring, D, of about three-eighths of an inch diameter, and of about one-sixteenth of an inch diameter spring-wire. A second open link, E, attached to the lower end of the spiral spring by an integral eye, D', serves to put any requisite grip upon the movable jaw or bow B, and a screw-eye pin, F, bearing against the lower inner edge of the link E, retains the spring at the desired tension.

To put the device into working form, a pole, G, of suitable length being provided, the bows or jaws A B, interlocked with each other upon the bar I, as described, are set vertically upon the end of the pole G, and the free or tang ends A² of the fixed jaw or bow A are driven into the end of the same, the bar I keeping the device in a firm and operative condition thereon. The spiral spring D being connected, as described, to the looped levers B² of the movable jaw or bow B, it is drawn downward by the link E, and the screw-eye pin F inserted into the pole G. This makes a picker out of the combination by the simple attachment of a cord to the top of the movable bow B; but if so used the fruit would drop to the ground and be bruised. To prevent such bruising and enable the operator to gather the most delicate fruits without injury to the same, I cover the fixed bow A with a light but strong fabric, leaving a tail of the same material projecting some two or more inches below the bar I. To the movable bow or jaw B, I attach by its edges an open-mouth tube, H, connecting the same to the fixed cover of the fixed bow by the tail-piece described. The tube is made of such length that it shall reach from the top of the pole to the usual fruit-gathering bag suspended from the shoulders of the operator, and of such diameter as will pass the fruit to be picked.

To operate the complete device, the pole is raised to the fruit to be picked, the movable jaw B is made to open by pulling upon the tube H, and, the fruit being caught between the two jaws or bows A B and the tube released, the fruit is caught between and pulled from the branch, and drops through the tube H to the

bag of the operator. Resistance to the rapid descent of the fruit is obtained by grasping the tube above the bag or twisting the same.

I make no claim to the tube as a chute for 5 the fruit, as I am aware that it is an old device; but I believe myself to be the first to attach it to the movable jaw, and to use it for both an operating and fruit-delivering purpose.

10 I am also aware that wire frames have been used for fruit-pickers prior to my invention; but I also believe that I am the first to increase the gripping force of the movable jaw by a spiral-spring re-enforce connection with the 15 free inner looped ends of the same.

Having shown the construction, operation, and advantages of my improved fruit-picker, I desire to secure by Letters Patent the following claims thereon:

20 1. In a fruit-picker constructed substan-

tially as shown and described, the combination of the re-enforce tensional spring D with the movable tube-frame B of the tube H by eyes D', links C E, looped lever-arms B², bar I, pole G, and pin F, substantially as and for 25 the purpose specified.

2. In a fruit-picker constructed substantially as shown and described, the combination of the fixed covered frame A, the movable tube-mouth frame or jaw B, stiffening-bar 30 I, coil A', tangs A², springs B', looped lever-arms B², link C, re-enforce spring D, eyes D', link E, pin F, pole G, and tube H, all arranged and adapted to be operated as and for the purpose set forth.

CHARLES S. HILL.
